(57) **CLAIM**

The ornamental design for a Bluetooth headphone, as shown and described.

DESCRIPTION

FIG. 1 is a perspective view of a first embodiment of a Bluetooth headphone showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second embodiment of the Bluetooth headphone showing my new design;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof;

FIG. 16 is a perspective view of a third embodiment of the Bluetooth headphone showing my new design;

FIG. 17 is a front elevational view thereof;

FIG. 18 is a rear elevational view thereof;

FIG. 19 is a left side elevational view thereof;

FIG. 20 is a right side elevational view thereof;

FIG. 21 is a top plan view thereof;

FIG. 22 is a bottom plan view thereof;

FIG. 23 is a perspective view of a fourth embodiment of the Bluetooth headphone showing my new design;

FIG. 24 is a front elevational view thereof;

FIG. 25 is a rear elevational view thereof;

FIG. 26 is a left side elevational view thereof;

FIG. 27 is a right side elevational view thereof;

FIG. 28 is a top plan view thereof;

FIG. 29 is a bottom plan view thereof;

FIG. 30 is a perspective view of a fifth embodiment of the Bluetooth headphone showing my new design;

FIG. 31 is a front elevational view thereof;

FIG. 32 is a rear elevational view thereof;

FIG. 33 is a left side elevational view thereof;

FIG. 34 is a right side elevational view thereof;

FIG. 35 is a top plan view thereof;

FIG. 36 is a bottom plan view thereof;

FIG. 37 is a perspective view of a sixth embodiment of the Bluetooth headphone showing my new design;

FIG. 38 is a front elevational view thereof;

FIG. 39 is a rear elevational view thereof;

FIG. 40 is a left side elevational view thereof;

FIG. 41 is a right side elevational view thereof;

FIG. 42 is a top plan view thereof;

FIG. 43 is a bottom plan view thereof;

(Continued)

FIG. 41 is a perspective view of a seventh embodiment of the Bluetooth headphone showing my new design;
FIG. 45 is a front elevational view thereof;
FIG. 46 is a rear elevational view thereof;
FIG. 47 is a left side elevational view thereof;
FIG. 48 is a right side elevational view thereof;
FIG. 49 is a top plan view thereof;
FIG. 50 is a bottom plan view thereof;
FIG. 51 is a perspective view of a eighth embodiment of the Bluetooth headphone showing my new design;
FIG. 52 is a front elevational view thereof;
FIG. 53 is a rear elevational view thereof;
FIG. 54 is a left side elevational view thereof;
FIG. 55 is a right side elevational view thereof;
FIG. 56 is a top plan view thereof; and,
FIG. 57 is a bottom plan view thereof.
The broken lines in the drawings depict portions of the Bluetooth headphone that form no part of the claimed design.
